WATER HEATER

Carroll W. Montgomery, Clarence Center, N. Y.

Application October 22, 1951, Serial No. 252,523

7 Claims. (Cl. 122—19)

1

This invention relates to a water heater and particularly to a water heater that can be used to produce either hot water or steam.

In the operation of producing hot water or steam it is desirable to provide a water heater in which substantially all of the heat produced by the fuel is transmitted to the water or steam. In the water heater as heretofore constructed a material quantity of the heat generated by the fuel is lost by passing out the flue or stack.

The present invention relates to a hot water heater having means for transferring substantially all of the heat generated by the fuel into the water. The invention further provides means for conserving any heat that is passed through the flue by means of a coil or preheater arranged in the flue. The present invention provides a substantially cylindrical water tank with a dome at the top thereof and a plurality of pipes in spiral formation connected to the body adjacent the bottom thereof and spirally upward through the firebox and being connected to the dome. The outlet pipe for the heater extends upwardly through the flue and also in the flue is arranged a preheater coil in the water inlet pipe.

It is accordingly an object of this invention to provide an improved water heater.

It is an object of this invention to provide a water heater having a plurality of spiral coils extending upwardly through the firebox.

It is a further object of this invention to provide a water heater having an enlarged dome at the top thereof.

It is a further object of this invention to provide a dome having a plurality of heat absorbing fins thereon.

It is a further object of this invention to provide a water heater having a preheater in the outlet flue thereof.

It is still a further object of this invention to provide a float operated valve to control the amount of water in a water heater.

It is a further object of this invention to provide a float operated valve of such dimensions that it can be entered through the water intake connection.

Other objects and many of the attendant advantages of this invention will be apparent from the following detailed description taken in conjunction with the accompanying drawings, in which:

Figure 1 is a vertical sectional elevation through the steam generator according to this invention;

2

Figure 2 is a cross section through the steam generator taken substantially on the plane indicated by the line 2—2 of Figure 1;

Figure 3 is an enlarged sectional elevation of the float valve;

Figure 4 is a view similar to Figure 1 showing a modification; and

Figure 5 is a cross section through the dome taken substantially on the plane indicated by the line 5—5 of Figure 4.

In an exemplary embodiment according to the invention the hot water heater has a body 10 of substantially cylindrical formation standing substantially vertical. The hot water heater comprises an enlarged dome into which the body 10 opens at the bottom thereof. The main heat transfer units comprise a pair of coils 14 and 16 having the lower ends communicating with the body 10 adjacent the bottom end thereof and spiraling upward through the firebox 18 and terminating in communication with the dome at the top of the firebox 18. The firebox 18 comprises an outer shell 20 of metal the major portion of which has a lining 22 of refractory material therein. The dome 12 is substantially oval in vertical section and the outside thereof is provided with a plurality of fins 24. The wall 20 curves substantially around the fins 24 so as to provide a restricted passage between the firebox 18 and a flue 26. The bottom end of the chamber 10 is substantially closed by a bottom 28 to which is threaded a substantially tubular water inlet connection 30. The tubular inlet connection 30 extends substantially axially in the body 10 and terminates in spaced relation from the bottom 28 preferably adjacent to the inlet openings of the spiral coils 14 and 16. This termination in spaced relation to the bottom of the tank provides a quiet space in which any sediment or dirt or other materials in the water will settle and be substantially trapped out of the circulating system.

A suitable burner 32 is placed in the bottom of the firebox and immediately surrounding the body 10. A suitable gaseous fuel is introduced into the burner 32 and escapes through the ports 34 where it is consumed and the hot gases pass upwardly around the body 10 and particularly around the spiral coils 14 and 16 transferring the majority of heat through the water in the coils 14 and 16, the hot gases continue upwardly around the dome 12 where the fins 24 extract a further portion of the heat so that a substantially small portion of the heat escapes through the flue 26.

To further conserve any heat that escapes through the flue the outlet pipe 36 extends upwardly from the dome 12 through the flue 26 and connects to a circulating system not shown. The water inlet conduit 38 has a coil, 40 therein, the coil 40 is arranged in the flue 26 so that any heat escaping through the flue 26 will be transmitted to the intake water in the coil 40.

The water inlet conduit 38 extends down around the firebox 18 and connects to a fitting 42 attached to the external end of the water inlet 30. Preferably the firebox 18 or rather the jacket of the firebox 20 is provided with a heavy insulating jacket 44 which is usually retained in place by means of an external sheeting 46. While the sheeting 46 corresponds substantially in shape to the firebox 18 it may, of course, be changed or modified to provide an ornamental effect if desired.

That portion of the inlet conduit 38 extending from the coil 40 to the fitting 42 is substantially embedded within the insulation within the outer jacket 46. A return pipe from circulating system 48 connects to the inlet conduit 38 between the coil and the fitting 42 preferably by means of a T-connection 50 somewhere intermediate the coil and a union 56 placed in the conduit 38 adjacent to the fitting 42. A check valve 52 is placed in a connection 58 between the return pipe 48 and the preheater 40.

It is desirable to have a check valve 54 between the inlet 30 and the circulating system as indicated at 48 and preferably this valve is also placed within the inlet conduit between the fitting 42 and the fitting 50.

The arrangement as so far described is particularly useful when hot water is to be used as a circulating medium. However, if steam is to be the circulating medium it is desired to provide a water level within the body 19 and have superheated steam within the dome 12 so that the circulating fluid will be steam. However, the return inlet 48 will carry condensed steam or just water. In order to convert the device to a steam generator a valve 60 is placed in the water inlet 30, the seat 62 of the valve 60 being arranged on the interior of the fitting 42 having the movable valve 66 seated on a conical surface 64 thereon. A float 66 is connected to the valve 66 by means of a suitable flexible connection such as a chain 68. The float 66 is an elongated substantially tubular member of such diameter that readily passes through the water inlet 30. For the adjustment of the valve seat 62 and the introduction of the float controlled valve, the fitting 42 is provided with a passage 70 closed by means of a plug 72, the passage 70 being as large or larger than the passage through the water inlet 30 so that the float, the valve and the valve seat may be introduced through the fitting 42 and the valve seat 62 screwed into position in the fitting 42.

A safety valve 75 is provided with a tube 76 in communication with the dome 12. Likewise a pressure gauge 78 is provided with a tube 80 in communication with the dome 12.

A water gauge is provided by means of a tube 84 connected into the fitting 42 on the tank side of the valve 60 and extending by means of suitable fittings 86 outwardly and upwardly along the outside of the outer cover 46 and extending back and welded into the body 19 above the position of the float 66 and preferably below the dome 12. A suitable sight glass or water glass 88 may be connected to the tube 86 preferably adja-

cent the location of the float 66 so that the water level may be suitably observed therein.

In the operation the device as a straight water heater the entire device including the dome is filled with water which circulates through the pipes 36 to 48 by means of a thermo-siphon action.

To operate the device as a steam generator, water is admitted until the float valve 66 seats the valve 60 at which time the ingress of water is stopped. The water in the coils 14 and 16 will be turned to steam and ejected into the dome 12 to produce a circulation of water from the body 19 into the coils and steam into the dome 12. Steam will go out through the outlet pipe 36 while the water or condensed steam will return through the return pipe 48.

While an exemplary embodiment has been shown and particularly described according to the best present understanding thereof will be apparent and changes and modifications can be made therein without departing from the true spirit of the invention.

Having described the invention, what is claimed as new is:

1. A water heater comprising a substantially cylindrical body, an enlarged dome on said body, a plurality of tubes communicating with said body intermediate the ends thereof and terminating in said dome, a burner around said body adjacent the lower end thereof, a heat chamber around said body and said dome, a refractory lining in a major portion of said chamber, a flue communicating with the top of said chamber, an outlet on the top of said dome, said outlet extending through said flue, an inlet conduit, a coil in said inlet conduit, said coil being arranged in said flue, said inlet conduit connecting into the bottom of said body, a return conduit, said return conduit connected to said inlet conduit between said coil and the bottom of said body, a check valve in said inlet conduit between said coil and said return conduit.

2. A water heater comprising a substantially cylindrical body, an enlarged dome on said body, a plurality of tubes communicating with said body intermediate the ends thereof and terminating in said dome, a burner around said body adjacent the lower end thereof, a heat chamber around said body and said dome, a refractory lining in a major portion of said chamber, a flue communicating with the top of said chamber, an outlet on the top of said dome, said outlet extending through said flue, an inlet conduit, a coil in said inlet conduit, said coil being arranged in said flue, said inlet conduit connecting into the bottom of said body, a return conduit, said return conduit connected to said inlet conduit between said coil and the bottom of said body, a check valve in said inlet conduit between said coil and said return conduit, a float operated valve in said inlet connection.

3. A water heater comprising a substantially vertically extending cylinder, an enlarged dome on said body, a firebox surrounding said body, a refractory lining in said firebox, a spiral coil arranged in said firebox, the lower end of said coil communicating to said body adjacent the lower portion thereof, the top end of said coil communicating to said dome, a water inlet connection including a tubular member extending through the bottom of said body and terminating in spaced relation to the bottom of said body, a flue on said firebox, a passage around said dome, fins on the outer surface of said dome in

said passage, an outlet pipe on said dome, said outlet pipe extending through said flue, an inlet conduit connected to said water inlet connection, a coil in said inlet conduit, said coil arranged in said flue.

4. A water heater comprising a substantially vertically extending cylinder, an enlarged dome on said body, a firebox surrounding said body, a refractory lining in said firebox, a spiral coil arranged in said firebox, the lower end of said coil communicating to said body adjacent the lower portion thereof, the top end of said coil communicating to said dome, a water inlet connection including a tubular member extending through the bottom of said body and terminating in spaced relation to the bottom of said body, a flue on said firebox, a passage around said dome, fins on the outer surface of said dome in said passage, an outlet pipe on said dome, said outlet pipe extending through said flue, an inlet conduit connected to said water inlet connection, a coil in said inlet conduit, said coil arranged in said flue, a return pipe to said heater, said return pipe connected to said inlet conduit between said coil and said inlet connection.

5. A water heater comprising a substantially vertically extending cylinder, an enlarged dome on said body, a firebox surrounding said body, a refractory lining in said firebox, a spiral coil arranged in said firebox, the lower end of said coil communicating to said body adjacent the lower portion thereof, the top end of said coil communicating to said dome, a water inlet connection including a tubular member extending through the bottom of said body and terminating in spaced relation to the bottom of said body, a flue on said firebox, a passage around said dome, fins on the outer surface of said dome in said passage, an outlet pipe on said dome, said outlet pipe extending through said flue, an inlet conduit connected to said water inlet connection, a coil in said inlet conduit, said coil arranged in said flue, a return pipe to said heater, said return pipe connected to said inlet conduit between said coil and said inlet connection, a check valve in said inlet conduit between said coil and the connection to said return pipe.

6. A water heater comprising a substantially vertically extending cylinder, an enlarged dome on said body, a firebox surrounding said body, a

refractory lining in said firebox, a spiral coil arranged in said firebox, the lower end of said coil communicating to said body adjacent the lower portion thereof, the top end of said coil communicating to said dome, a water inlet connection including a tubular member extending through the bottom of said body and terminating in spaced relation to the bottom of said body, a flue on said firebox, a passage around said dome, fins on the outer surface of said dome in said passage, an outlet pipe on said dome, said outlet pipe extending through said flue, an inlet conduit connected to said water inlet connection, a coil in said inlet conduit, said coil arranged in said flue, a return pipe to said heater, said return pipe connected to said conduit between said coil and said inlet connection, a check valve in said inlet conduit between said coil and the connection to said return pipe, a valve in said water inlet connection, a float in said body, means operatively connecting said float to said valve.

7. A water heater comprising a substantially vertically extending cylinder, an enlarged dome on said body, a firebox surrounding said body, a refractory lining in said firebox, a spiral coil arranged in said firebox, the lower end of said coil communicating to said body adjacent the lower portion thereof, the top end of said coil communicating to said dome, a water inlet connection including a tubular member extending through the bottom of said body and terminating in spaced relation to the bottom of said body, a valve in said water inlet connection, a float in said body operatively connected to said valve, said float being an elongated member of a diameter sufficiently small to pass through said water inlet connection.
